UNITED STATES PATENT OFFICE

147,638

DESIGN FOR A COMBINED TOOTHBRUSH
AND TUMBLER HOLDER

Frank D. Busker, Libertyville, Ill.

Application July 9, 1946, Serial No. 131,428

Term of patent 3½ years

(Cl. D4—3)

To all whom it may concern:

Be it known that I, Frank D. Busker, a citizen of the United States, residing at Libertyville, in the county of Lake and State of Illinois, have invented a new, original, and ornamental Design for a Combined Toothbrush and Tumbler Holder, of which the following is a specification, reference being had to the accompanying drawing, forming part thereof.

Figure 1 is a perspective view of a combined toothbrush and tumbler holder, showing my new design and illustrating the same in the closed position.

I claim:

The ornamental design for a combined toothbrush and tumbler holder, as shown.

FRANK D. BUSKER.
